(No Model.)

J. A. BONNELL.
DERAILING SWITCH.

No. 341,400.

Patented May 4, 1886.

UNITED STATES PATENT OFFICE.

JAMES A. BONNELL, OF BROOKLYN, NEW YORK.

DERAILING-SWITCH.

SPECIFICATION forming part of Letters Patent No. 341,400, dated May 4, 1886.

Application filed January 5, 1885. Serial No. 152,239. (No model.)

To all whom it may concern:

Be it known that I, JAMES A. BONNELL, a citizen of the United States, and a resident of Brooklyn, in the county of Kings and State of New York, have invented certain new and useful Improvements in Derailing-Switches, of which the following is a specification.

My invention relates to a derailing-switch for use at grade-crossings, junctions, draw-
bridges, &c., and to be operated simultaneously with the danger-signal to prevent collision between a stationary train and one proceeding, notwithstanding the said signal, by switching the latter train off from the track.

15 The invention consists in the combination, with a derailing single rail and switch-rail, of a switch-bar connected by a slip-joint to the operating-rod from the signal-house, and a switch-lock consisting of a single stop or keeper 20 and a crank-cam connected to the rod of the same hand-lever by which the switch is thrown.

In the accompanying drawings, Figure 1 represents a plan view of a derailing apparatus constructed according to my present invention. 25 Fig. 2 is a detail section of the switch-bar and the cam-shaft and its bearings, the section being taken on the line *xx* of Fig. 1, and seen in the direction of arrow 1. Fig. 3 is a detail section on the line *yy*, seen in the direction of arrow 1, and showing a side view of the crank-cam. Fig. 4 shows the lock-keeper in direction of arrow 4.

In the drawings the switch is shown as being open, ready for derailing a train.

35 A A' are the rails of the main track, *a* the switch-rail, and *B* the third or derailing rail laid alongside of the rail *A*, and slightly and gradually diverging from it.

C is the switch-bar, provided with a stop or 40 keeper, *c*, which is curved on the side nearest to the rail, being gradually increasing in width from the point toward the base. The bar *C* has longitudinally a slot, *b*, through its free end, and in sliding it rests upon a plate, *D*, secured 45 to suitable sleepers or timbers, and to the under side of which is secured another plate provided with a lug or bearing, *d*, as seen in Fig. 2, to receive one end of the cam-shaft *E*, whose other end works in a bearing, *e*, secured un- 50 derneath the flange of the derailing-rail *B*.

F is a cam, mounted on the shaft *E*, and composed of a crank, *f*, and a toe, *e'*, at an angle

to the crank, which toe serves to lock the switch-rail *a* against *B* when the cam *f* is turned toward the said rail to engage the keeper or 55 stop *c*. Connection from the crank *F* to the switch-lever rod *G* is made by rods *g h* and bell-cranks *H I*, attached together by suitable pivotal joints, as shown in the drawings.

J is another bell-crank, which, like the bell-cranks *H I*, is fulerumed to a casting embedded in the ground. The lever *J* is connected by a jaw with one arm to the rod *G*, and has fastened to the end of its other arm a pin, *i*, which works into the aforesaid slot *b* in the switch-bar *C*. The construction and arrangement of the rods and levers connecting the switch-bar and the locking-cam to the switch-lever rod *G* must of course be modified according to the location of the track and the ground. 70

The operation will be readily understood with reference to Fig. 1, all the parts of which are in position as when the switch is open to derail the train, so that one wheel thereof will run upon the rail *B*, while the opposite wheel 75 is off the rail *A* and runs upon the ties and ground of the track, as indicated in dotted lines in the drawings. The cam *F* is thrown back from the keeper *c*, there being no necessity of locking the switch when open. When the 80 switchman turns off the danger-signals to indicate "all clear," he at the same time moves the rod *G* in the direction of arrow 2, thereby turning the crank-cam *F* in the direction indicated by arrow 3 in Fig. 3, to cause the toe *e* 85 to approach the keeper *c*. In the meantime, by the turning of the crank *J* by the rod *G*, the pin *i* travels toward the outer end of the slot *b* without producing any movement of the switch-bar until it has reached the outer end 90 of the slot, when it pulls the bar with it, closing the switch-rail *a* against the rail *B*, to allow the train to proceed upon the main track. Just as the switch closes, the toe *e'* of the cam has turned far enough to engage the curved side 95 of the keeper *c*, proceeding downward, on which it tightens the switch-rail against the rail *B*, and finally stops with its straight under edge in contact with the upper surface of the switch-bar. 100

In order to again open the switch the bar *G* is of course moved in the direction opposite to that indicated by arrow 2, and the pin, traveling inward in the slot *b* without effecting any

movement, allows the switch-bar to remain at rest, while the cam F, for which no slip or movement is provided, rises clear of the keeper c just in time to allow the switch to be thrown 5 when the pin i has reached the inner end of the slot b.

Be it understood that anything herein contained which has been described and claimed in an application for a railway-switch operating and locking mechanism, and in another application for a railway-switch lock, both of which are filed simultaneously with this present, is hereby disclaimed.

Having thus described my invention, I claim 15 as new and desire to secure by Letters Patent—

The combination, with the track A A', de-

railing-rail B, and switch-rail a, of the switch-bar C, provided with the curve-faced stop or keeper c, and connected by a slip-joint, b i, and lever J to the switch-lever rod G, and the 20 crank cam F, connected by suitable rods and levers to the said rod G, to lock and unlock the switch by the movement of the switch-lever, all substantially as hereinbefore set forth.

In testimony that I claim the foregoing as 25 my invention I have signed my name, in presence of two witnesses, this 1st day of October, 1884.

JAMES A. BONNELL.
